UNITED STATES PATENT OFFICE.

ANDREW WOLFRAM, OF PITTSBURGH, PENNSYLVANIA.

MACHINE FOR MAKING NUTS.

Application filed April 18, 1924. Serial No. 707,876.

To all whom it may concern:

Be it known that I, ANDREW WOLFRAM, a citizen of the United States, and resident of Pittsburgh, in the county of Allegheny and 5 State of Pennsylvania, have invented a new and useful Improvement in Machines for Making Nuts; and I do hereby declare the following to be a full, clear, and exact description thereof.

10 My invention relates to machines for making nuts, and its general object is to provide a machine of simple and rugged construction which shall operate rapidly and automatically to produce finished nut blanks 15 from cold stock, and shall include the various mechanisms necessary for performing the operations of piercing, cutting, trimming, crowning and finishing.

More specifically, one object of my invention 20 is to provide a machine for making nuts wherein the punches which operate upon the blanks are arranged to move in a horizontal path and co-operate with dies having their axes horizontal so that the chips produced at the dies will fall away without clogging or otherwise interfering with the dies, and without the need for stock breakers interposed between the dies.

Another object of my invention is to provide a machine for making nuts in which the bar or strip from which the nuts are to be made are fed into the machine in a step by step manner, and is released by the feeding mechanism during the time when the punches engage the bar, thus permitting the bar to be properly positioned with respect to the punches without interference by the feeding mechanism.

A further object of my invention is to 40 provide a machine for making nuts having a safety device for throwing the machine out of operation in case the nut blanks become jammed in the dies.

A still further object of my invention is 45 to provide a machine for making nuts having two or more trimming dies, the use of a plurality of trimming dies being rendered possible by horizontal arrangement of the punches and dies, which prevents fouling of the dies with chips which would occur if two or more trimming dies were placed one above the other.

A still further object of my invention is 50 to provide a novel feeding mechanism which may be thrown into and out of operation

independently of the automatic movement of the machine.

A still further object of my invention is to provide a novel mechanism for transferring blanks from one die to another. 60

Other objects and advantages of my invention will appear from the following description taken in connection with the accompanying drawings, in which—

Fig. 1 is a plan view showing the general 65 construction of a machine constructed in accordance with my invention; Fig. 2 is a side elevational view of the same machine; Fig. 3 is a partial side elevational view taken from the opposite side of the machine 70 with respect to Fig. 2; Fig. 4 is an enlarged plan view of the dies and the transfer mechanism; Fig. 5 is an inverted side elevational view of the mechanism shown in Fig. 4, as seen from the top of Fig. 4; Fig. 6 is 75 a side elevational view of the transfer mechanism as seen from the right of Fig. 4; Fig. 7 is an enlarged plan view, partly in section, of the feeding mechanism and the dies; and Figs. 8 and 9 are details of the 80 clutch mechanism between the driving gear and crank shaft of the machine.

The machine shown in the drawing comprises a frame composed of side members 2, 85 an end member 3, a transverse die-supporting body 4 at the opposite end of the machine frame and supporting legs 5. A drive shaft 6 is mounted in suitable bearings 7 in the machine frame and carries at one end a pulley 8, which may be connected to any 90 suitable source of power, not shown. The shaft 6 carries at its opposite end a pinion 9 which meshes with a spur gear wheel 10 that is mounted loosely on the projecting end of a main shaft 11, which is mounted in 95 bearings 12 and 13 on the machine frame.

The main shaft 11 is provided between the bearings 12 and 13 with an eccentric portion which is enclosed within a concentric housing 14 that is connected by means of a pitman 15 to reciprocate a punch slide 16 which is mounted in suitable guide ways in the machine frame, and which is held in position in the guide ways by means of plates 17. 100

The end of the main shaft 11 opposite to 105 the gear wheel 10 is reduced in diameter and carries a cam 18 for operating the transfer mechanism, a cam 19 for operating the lateral stock feeder, and a cam 20 for operating the presser foot which forms a part of the 110

feeding mechanism. The cams 18, 19 and 20 cooperate with cam rollers 21, 22 and 23, respectively, which are carried in forks formed at the ends of horizontal sliding bars 24, 25 and 26, that are mounted to slide in fixed guide ways carried by brackets 27 and 28 extending laterally from one of the side members 2 of the machine frame.

10 *Feeding mechanism.*

The feeding mechanism includes two main pressure members 30 and 31 which periodically clamp between them the bar 33 from which the ends are to be formed and advance this bar toward the dies in a step by step manner. Both of these pressure members are mounted to swing about a fixed pivot, and the member 30 is also given a movement toward and away from the stock so as to alternately grip the stock and release it. The outer pressure bar 31 with its attachments is mounted upon a swinging member 34 which, as best shown in Fig. 2, is offset between its ends and is pivotally mounted at its inner end upon a bolt 35, which is screwed up into a bracket 36 which is secured to one of the side members 2 of the machine frame by means of bolts 37. The bracket 36 also carries the guide ways for the cam bars 24, 25 and 26 described above. The swinging member 34 is offset between its ends, as shown in Fig. 2, and its upper and outer portion rests slidably upon a bracket 38 which is secured to the side of the machine frame by means of bolts 39. A spring 40 is connected between the member 34 and an extension 41 of the bracket 38.

The swinging member 34 has an enlargement 45 in which is formed a recess 46 covered by a stripper plate 47. Fitting loosely within the recess 46 is a block 47^a provided with recesses 48 in which are received springs 49 that surround screws 50. These screws are extended into tapped openings in the outer pressure member 31. The outer end of the block 47^a rests against the rounded end of a pin 51 which extends through an opening in the end of the enlargement 45 of the swinging member 34. The outer end of the pin 51 rests upon the spirally curved surface 52 of a cam member 53 that is mounted pivotally on an extension 54 of the swinging member 34 and is provided with a handle 55. When the handle 55 is in the position shown in Figs. 1 and 7, the pressure of the springs 49 is relieved from the presser block 31, and therefore the presser block 31 does not clamp the stock bar 33. The stock will then not be fed into the machine even though the feeding mechanism is otherwise in operation. When it is desired to start the feeding mechanism, the handle 55 is turned to the right, as seen in Fig. 7, and the cam 53 then acts through the pin 51 to move the block 50 toward the presser block 31,

This movement is communicated through the springs 48 to resiliently clamp the block 31 against the stock bar 33, this arrangement forming an automatic trip by which the feed may be thrown into and out of operation whenever desired.

The presser block 30 is secured removably by means of a set screw 55' in the holder 56 which rests upon the upper surface of the swinging member 34, and is provided with a slot 57 surrounding a pin 58 which projects upward from the member 34 and serves to guide the movement of the holder 56. The holder 56 is pivotally secured at 59, Fig. 7, to the outer end of a horizontal bar 60, the opposite end of which is pivotally secured at 61, Fig. 1, to a coupling 62 of adjustable length, which in turn is secured to the sliding bar 26, that is reciprocated, as stated above, by means of the cam 20, carried by the main shaft 11. This joint connection between the holder 56 and the operating cam 20 permits the holder 56 to not only move toward and away from the stock bar 33, but also to swing with the member 34. The holder 56 also has independent rocking movement around its pivotal connection 59 so as to accommodate itself to the surface of the stock bar during the sliding movement of the member 34. A spring 63 is connected between the pin 59 of the holder 56 and a fixed pin 64 carried by the bracket 27. This spring tends to move the holder 56 away from the stock bar 33 in opposition to the cam 20.

100 The feeding movement of the presser block 30 is produced by means of a cam 65 formed on the outer end of the bar 25 which is reciprocated by means of the cam 19. The cam 65 engages a roller 66 carried by the presser block holder 56. When the cam bar 28 is forced to the left, Fig. 1, by the cam 19, the cam surface 65 acts through the roller 66 to move the presser block holder 56 in the direction to feed the stock bar into the machine. This movement causes the entire feeding mechanism carried by the swinging member 34 to swing around the pivot of the member 34, thereby stretching the spring 40. A spring 67 is connected to 110 retract the cam bar 65 when this bar is released by the cam 19, and the spring 40 thereupon returns the swinging member 34 with its attachments until the roller 66 engages a projection 68 upon the end of the cam bar 65.

115 In the operation of the feeding mechanism just described, the trip handle 55 is moved to the open position shown in the drawings, the stock bar 33 is inserted between the presser blocks 30 and 31 and the handle 55 is turned to clamp the presser block against the stock bar. Assuming that the main shaft of the machine is now in operation, the cam 20 moves the bar 26 to the left, 120 125

Fig. 1, thereby clamping the presser block 30 against the stock bar, and thereupon the cam 19 moves the cam bar 25 to the left, as seen in Fig. 1, thereby rocking the entire feeding device around the pivot of the member 34, thereby advancing the stock bar 33 to bring the end portion of the bar beneath the dies which are presently to be described. At this moment one of the novel features of my invention comes into play, this is the release of the stock by the feeding mechanism before the dies are operating upon the stock, after which the presser block again engages the stock bar and holds it firmly while the dies are operating on the stock. For this purpose, the cam 20, which controls the pressure of the block 30 upon the stock bar, is caused to release its pressure upon the cam roller 23 momentarily and then to again force the presser block 30 against the stock bar. The contour of the cam 20, which produces this action, is seen in Fig. 2, and includes a concentric dwell 70 which permits the presser block to be retracted from the stock bar, a projecting dwell 71 which forces the presser block against the stock bar during the initial feeding movement, a relieved dwell portion 72 which releases pressure upon the presser block while the stock is being centered opposite to the dies, and a second projecting dwell 73 which causes the presser block to clamp the stock bar during the operation of the punches.

While the stock bar is being advanced toward the dies, the presser blocks 30 and 31 are moved in an arcuate path around the pivot of the swinging member 34. However, both of these blocks are able to maintain their clamping surfaces in engagement with the straight sides of the stock bar 33 since the presser block 30 is pivotally mounted on the pin 59, while the opposite presser block 31 is resiliently mounted on the springs 49.

The slide 16 carries at its forward end a punch block 75 which is adjustable vertically, and carries a piercing punch 76, a roughing punch 77, a crowning punch 78 and a trimming punch 79, these punches being successively farther advanced from the face of the punch block 75, as seen on Figs. 1 and 7.

Opposite to the piercing and roughing punches is a series of dies including a die 80 having a round opening 81, an intermediate die 82 having a hexagonal opening 83, and a third die 84 having a hexagonal opening 85. The dies 80, 82 and 84 are supported by suitable spacers 86. The first die member 80 is extended to a position opposite to the piercing punch 76 and is there provided with an opening 87 to admit the piercing punch 76. The metal punched from the stock bar 33 by the piercing punch 76 is forced through the opening 87 into a

larger opening 88 formed in the block 89 which carries the dies. This waste material is able to fall freely out of the machine since the opening 88 is vertical. Similarly, the chips and waste produced when the roughing die 77 cuts any blanks from the stock bar and forces the blanks through the successive dies 80, 82 and 84, are able to fall freely out of the machine through the space between the dies. Fouling of the dies by such chips and waste is thereby prevented.

The stock bar 33 is guided at the piercing and cutting positions by means of a plate 90 which is secured to the die block 89 and is spaced therefrom centrally to admit the stock bar 33. The plate 90 has an opening 91 of proper size to admit the piercing punch 76.

The blanks cut off successively from the stock bar 33 are forced one after another through the set of dies 80, 82 and 84, each nut blank being pushed forward by the blanks which follow it. When each blank emerges from the die 84 it enters a slot 92 in the die block 89 and is pushed laterally into position opposite to a crowning die 93 by means of a pusher rod 94, which forms a part of the transfer mechanism which will be described below. In this position the blank is crowned by means of the crowning punch 78, being held at this time between upper and lower guide strips 95 and 96. Another portion of the transfer mechanism then transfers the crowned blank from the crowning die to a position opposite to two or more finishing or trimming dies 97 and 98, which are supported by suitable spacers 99. The trimming punch 79 forces the blanks through the dies 97 and 98, and the finished blanks emerge from the die 98 into a horizontal channel 100 in the die block 89 which communicates with a similar channel 101 in the frame member 4, as seen in Fig. 1, and the finished nut blanks drop out of this channel into any suitable receptacle.

Transfer mechanism.

The partially formed nut blanks are transferred in succession from the roughing dies to the crowning die and thence to the trimming dies by means of a set of transfer mechanism which is operated by a horizontal rod 105 which is mounted slidably in bearings 106 that are secured to the top of the die block 89. The rod 105 is reciprocated lengthwise by power derived from the cam 18 on the main shaft 11 through the cam roller 21, the sliding bar 24, a cam member 107 carried by the bar 24, a horizontal bar 108 having a cam roller 109 engaging the cam 107, and having an enlarged end 110 engaging a roller 111 carried by a lever 112 which is mounted on a fixed pivot 113, and is loosely pivoted at its end opposite to the roller 111 to one end of the rod 105. A spring 110

115 tends to retract the cam member 107 in opposition to the cam 18, and a spring 116 which is connected between the lever 112 and a fixed bracket 117 tends to move the rod 105 to the position shown in Fig. 1, the action of the spring 116 being also in opposition to the cam 18. Through these connections the cam 18 moves the rod 105 to the left, as seen in Figs. 4 and 5, and upwardly as seen in Fig. 1, while the spring 116 moves the rod 105 in the opposite direction.

A pusher rod 94 which, as stated above, pushes the partially formed nuts from the roughing dies to the crowning die, is secured to the end of the rod 105 opposite to the lever 112 by means of a strap 120 having eyes 121 and 122 formed in its opposite ends, and set screws 123 for securing the strap 120 to the rods 105 and 94, as best shown in Fig. 5.

The mechanism which transfers the nuts from the crowning die to the trimming or finishing dies, is best shown in Figs. 4, 5 and 6. This mechanism includes an arm 125 which is pivotally mounted on a horizontal pin 126, the ends of which are secured in the parallel arms 127 of a bracket 128, which is mounted slidably on the rectangular rod 105, and is secured in adjusted position thereon by means of a set screw 129. The arm 125 carries at its lower end an enlarged finger 130 which is provided with a notch 131 for engaging the nut blanks. A compression spring 132 is connected between opposed recesses in the arm 125 and in the bracket 128, and tends to maintain the arms 125 in the vertical position shown in Fig. 6, this normal position of the arm 125 being adjustable by means of a set screw 133, the end of which bears against the bracket 128.

When the mechanism is in the position shown inverted in Fig. 5, the notch 131 of the finger 130 is in position behind the crowning die 93, and when the rod 105 moves to the right as seen in Figs. 4 and 5, the finger 130 of the arm 125 pushes the nut from the crowning die 93 to a position above the trimming dies 97 and 98. At the same time the nut is pushed from the roughing die to the crowning die by means of the pusher rod 94, and it is therefore necessary that the finger 130 be moved aside on its return stroke so as not to interfere with the nut that has just been placed on the crowning die. For the purpose of deflecting the arm 125 at this time, the upper end of the arm 125 is provided with a projecting pin 135, which moves adjacent to a deflecting cam 136 which is mounted pivotally on a bolt 137 that is carried by the upper horizontal arm of a stationary Z-bar 138. The cam 136 has a downwardly extending working portion 139 which is provided at one end with an inclined projection 140 and is deflected at its opposite end, as shown at 141.

The cam is normally held in the position shown in Figs. 4 and 6 by means of a spring 142 which is connected between a stationary pin 143 on the bracket 138, and a pin 144 which is carried by the cam 136 and projects upwardly through a slot 145 in the bracket 138, as shown in Fig. 4. In this position of the cam 136 its outer edge rests flat against the front wall 146 of a recess 147 in the bracket 138, which contains the body of the cam 136. When the rod 105 moves to the right in Figs. 4 and 5, the pin 135 of the arm 125 engages the inclined projection 140 of the cam 136 and deflects the cam downwardly as seen in Fig. 4, and to the left as seen in Fig. 6. As soon as the pin 135 passes the projection 140, the cam 136 is returned to its normal position by the spring 142. On the return stroke of the rod 105, the pin 135 engages the outer surface of the projection 140 of the cam 136 and is thereby deflected downwardly as seen in Fig. 4, and to the left as seen in Fig. 6. This results in tilting the arm 125 around its pivot 126 in a counter-clockwise direction, as seen in Fig. 6, and the parts are so proportioned that this tilting of the rod 125 is sufficient to deflect the finger 130 so that this finger passes the crowning die without touching the nut which has then been placed opposite to the crowning die of the pusher finger 94.

The nuts are positioned properly opposite to the trimming dies 97 and 98 by means of fingers 150 which are arranged on opposite sides of the opening of the trimming die 97, as best shown in Fig. 5, and are connected by a spring 151 which moves the fingers 150 to an extent limited by adjustable stop screws 152 which are engaged by right angled extensions 153 of the fingers 150.

The gear wheel 10, which is mounted loosely on the shaft 11, is connected to drive the shaft 11 through a key 155 which is adjustably mounted in recesses formed in the hub of the gear wheel 10 and in the adjacent enlarged portion 157 of the shaft 11. The key 155 is normally pressed by means of a spring 158 into the position in which it connects the gear wheel 10 to the shaft 11. The key 155 is also provided with a slot 159 having a beveled outer portion 160 which is adapted to co-operate with a similarly beveled portion 161 of a key drawer 162. The key drawer is pivoted at 163 to a bracket 164 which projects outwardly from the side member 2 of the frame. A spring 165 is connected between the key drawer 162 and a stationary pin 166 and tends to hold the key drawer in the position shown in Figs. 1 and 3, at which time the key drawer 162 has entered the slot 159 and has withdrawn the key 155 from engagement with the gear wheel 10, thereby compressing the spring 158. A rod 167 is pivotally connected at

one end of the key drawer 162 and is pivotally connected at its opposite end to a horizontal hand lever 168 which is supported pivotally on a pin 169 carried by a bracket 170 extending outwardly from the bed member. The outer portion of the hand lever 168 is composed of two overlapping members which are connected together by means of a permanent bolt 171 and a shearing pin 172, as shown in Fig. 1. Near its outer end the hand lever 168 is received in an L-shaped bracket 173 which has a recess 174 for holding the lever in the position shown in dotted lines in Fig. 1, which is the position of this lever when the machine is running. The lever 168 is given sufficient vertical play to allow the lever to be lifted from the notch 174 when it is desired to stop the machine, and when this is done, the spring 165 moves the key drawer 162 into the slot of the key 155 when the next revolution of the shaft 11 brings the beveled notch of the key into engagement with the beveled end of the key drawer.

If it should happen that the nut blanks should be improperly delivered from the roughing dies so as not to be transferred properly by the pusher rod 94, the thrust of the improperly delivered nut will be exerted against the end of a horizontal rod 175 which extends from the roughing dies to a position opposite to that portion of the hand lever 168 which carries the shearing pin 172. It will be seen on Fig. 1 that the outer end of the rod 175 is closely adjacent to the lever 168 when the lever is in its dotted line or running position. If the rod 175 is forced outwardly by the improper delivery of blanks from the roughing dies, this movement shears off the shearing pin 172 and permits the spring 165 to move the key drawer into position to stop the machine in the same manner as when the lever is moved from the dotted position in Fig. 1 to the full-line position. This arrangement provides a safety device for insuring that the machine will not be damaged through the improper delivery of blanks in the roughing dies.

I have shown and described in detail a construction of a machine which is well adapted for carrying out my invention. It will be understood, however, that various changes in the construction and arrangement of parts may be made without departing from my invention as set forth in the appended claims.

I claim as my invention:

1. Feeding mechanism for nut making machines comprising a pair of clamping members adapted to grip a stock bar between them, automatic means for reciprocating one of said clamping members toward and from the other, automatic means for swinging said clamping members around a fixed axis to advance said stock bar, and means for

permitting said clamping members to move about individual axes to maintain alignment with said stock bar during said swinging movement.

2. Feeding mechanism for nut making 70 machines, comprising a supporting member adapted to oscillate on a fixed pivot, a spring tending to hold said supporting member in one position, cam operated means for moving said supporting member in the opposite direction, a pair of clamping members carried by said supporting member, automatic means for reciprocating one of said clamping members toward and from clamping position, spring means for resiliently holding 80 the other in engagement with the stock bar, and a manually operable cam for throwing the last-named clamping member into and out of operation.

3. Feeding mechanism for nut making 85 machines comprising a supporting member adapted to oscillate upon a fixed pivot, a pair of clamping members carried by said supporting member, a spring tending to hold said supporting member in one position, cam operated means for moving said supporting member to advance a stock bar clamped between said clamping members, automatic means for moving one of said clamping members toward and away from the other, springs for resiliently pressing the second clamping member toward the other, and means for permitting said clamping members to attach themselves to the said stock bar while said clamping members are advancing said stock bar.

4. Feeding mechanism for nut making machines comprising a pair of clamping members adapted to grip and advance a stock bar, a set of dies and punches, and means for actuating said clamping members to advance said stock bar to said dies and punches, the said advancing means being arranged to release the stock bar after said stock bar is advanced to said dies and punches, and then to again grip said stock bar while said dies and punches are operating upon said stock bar.

5. Feeding mechanism for nut making 115 machines comprising a supporting member adapted to oscillate on a vertical axis, a clamping member, a holder for said clamping member mounted slidably and pivotally on said supporting member, cam-operated means for forcing said holder in one direction, a spring for retracting said holder in the opposite direction, a cam for moving said holder horizontally and for thereby swinging the said supporting member upon its vertical axis, a second clamping member 125 also carried by said supporting member, springs for yieldingly forcing said second-named clamping member toward said first-named clamping member, a block carrying said springs, a horizontal pin engaging said 130

- block, and a manually operable cam engaging said pin and adapted to move said pin lengthwise toward said clamping members, and thereby to force said second-named 5 clamping member toward said first-named clamping member.
6. A machine for making nuts comprising roughing, crowning and trimming dies, transfer mechanism for moving nut blanks 10 between said dies, comprising a pusher rod movable in a channel between said roughing dies and said crowning die, a shifting finger movable between said crowning dies and adapted to push nut blanks from said 15 crowning die to said trimming dies, and means for deflecting said finger on its return movement past said crowning die.
7. A machine for making nuts comprising a set of roughing, crowning and trimming 20 dies, a pusher rod for transferring nut blanks between said roughing and crowning dies, a reciprocating bar supporting said pusher rod, a transfer finger also carried by said bar, and means for deflecting said 25 transfer finger while said transfer finger is passing said crowning die in one direction, the said deflecting means comprising a cam pivotally mounted in the path of movement 30 of said finger, a spring normally holding said cam in position to engage and deflect said finger, and means carried by said finger for engaging and pushing aside said cam when said finger is moving in one direction, and for engaging said cam and deflecting 35 said finger when said finger is moved in the opposite direction.
8. A machine for making nuts comprising a set of dies arranged in line with one another, a punch co-operating with said dies, 40 a rod longitudinally movable in an opening arranged in line with the openings in said dies, a lever operably connected to control the movement of the machine, and a shearing pin arranged to be sheared by engagement with said lever.
9. A machine for making nuts comprising a set of roughing dies disposed in axial alignment, a crowning die spaced transversely of said roughing dies, and a plurality of 45 trimming dies spaced transversely of the crowning die and axially of the roughing dies.
10. A machine for making nuts comprising a set of roughing dies and a plurality of trimming dies, and means for transferring 55 a blank from one set of dies to the other set, the dies of each group being arranged in horizontal alignment, and each group being spaced in a direction axially of the other group. 60
11. A machine for making nuts comprising a set of roughing dies and a plurality of trimming dies, and means for transferring a blank from one set of dies to the other set, the dies of each group being arranged in 65 horizontal alignment and each group being spaced in a direction radially and axially of the other group.
12. A machine for making nuts comprising a set of punches arranged to reciprocate 70 horizontally, and a set of dies arranged to co-operate with the said punches, the said dies including a piercing die, a plurality of spaced roughing dies arranged in horizontal alignment with each other, a crowning die, 75 a plurality of spaced trimming dies arranged in horizontal alignment with each other and offset in directions radially and axially of the roughing dies, and means for transferring blanks to said sets of dies successively. 80
13. Feeding mechanism for nut making machines comprising a frame pivotally mounted upon a fixed axis, means for imparting intermittent oscillatory motion to said frame, clamping members adapted to 85 clamp a stock bar between them, automatic means for moving one of said clamping members toward and away from the other clamping member while said frame is at rest, and automatic means for moving said 90 oscillating frame to advance said stock bar when said clamping members are in clampeng engagement with said stock bar.
14. Feeding mechanism for nut making machines comprising a movable frame, 95 means for imparting intermittent advancing movements to said frame, stock bar clamping members on said frame, and means for operating said clamping members to temporarily release the bar when said frame is at 100 rest during periods between said movements.
- In testimony whereof I, the said ANDREW WOLFRAM, have hereunto set my hand.
- ANDREW WOLFRAM.
